AUTOMATIC RERECORDING SYSTEM

Carl N. Shipman, Rivera, Calif., assignor to Radio Corporation of America, a corporation of Delaware

Application December 31, 1956, Serial No. 631,683

11 Claims. (Cl. 179—100.1)

This invention relates to sound recording systems, and particularly to an automatic rerecording system whereby any manual adjustments of amplitude levels or other characteristics of a signal may be repeated automatically while permitting additional manual adjustments.

In Wolfe Patent No. 2,279,018 of April 7, 1942, an automatic sound rerecording system is disclosed and claimed, the Wolfe system utilizing variable gain amplifiers, a magnetic recorder for the control tracks and a mixing panel which varies the level of gain control frequencies applied to the variable gain amplifiers. The present invention is a simplification of the Wolfe system since it utilizes normal, standard audio signal attenuators, two attenuators being connected in series, one of which is adapted to be motor actuated from a control track and the other of which is adapted to be manually activated. The control track signal may be recorded on a first control track film and then recorded on a second control track film during a subsequent rehearsal. Also, a single film having both control tracks instead of audio tracks thereon may be used, as disclosed and claimed in Bradbury Patent No. 2,733,301 of January 31, 1956. By connecting two standard potentiometers in series, the potentiometers being on the attenuator shafts, and setting the motor controlled attenuator to its central or other fixed position during the actuation of the manual attenuator, and then setting the manual attenuator to the central or other fixed position during a subsequent reproduction, the proper amplitude or level control of the signal is obtained.

The principal object of the invention, therefore, is to provide an improved, automatic rerecording system by means of which the control of various signal characteristics is facilitated.

Another object of the invention is to provide an improved system for automatically repeating a rerecording operation.

A further object of the invention is to provide an improved system for duplicating the variations made in the transmission of electrical currents and to enable the making of manual changes during the duplication and re-transmission of the currents.

A still further object of the invention is to provide an improved rerecording system which is under the simultaneous control of both a control track and manual operation.

A better understanding of this invention may be had from the following detailed description when read in connection with the accompanying drawing in which the single figure is a combination diagrammatic and block diagram of a rerecording system embodying the invention.

Referring, now, to the drawing, the signal to be rerecorded is on a film 5 which is shown as a magnetic film detected by a magnetic reproduce head 6. Although magnetic film is illustrated as the source of the audio signals, it is to be understood that the sound tracks to

2

be rerecorded may also be on photographic film. In the present drawing, the magnetic head is connected over a conductor 7 to a standard attenuator 8, this attenuator being of the type now used in manual-operated rerecording systems. The attenuator 8 is connected over conductor 10 to a second standard attenuator 11, the output of which is fed over conductor 12 to a mixing network 13, then to an amplifier 14 and a recorder 15 when switch 52 is closed. The mixing network 13 may be fed from other similar channels as indicated by the conductors 17, two such audio sources being shown by films 20 and 21 with respective magnetic reproduce heads 22 and 23. A monitor 18 is connected to the mixing network 13.

The standard attenuator 8 has mounted on one end of its shaft 25 a motor unit 26 which may be either A. C. or D. C. depending on the type of control signal being used. The other end of the shaft 25 has connected thereto a potentiometer including a resistance element 28 and a slider 29, rotation of the shaft 25 varying the voltage between the ends of the resistor 28.

The standard attenuator 11 has mounted on its shaft 30 a knurled hand knob 31 of the type now being used with rerecording attenuators, and on the other end of its shaft a potentiometer 34 having a resistor element 32 and a slider 33. Thus, any changes made in the attenuators 8 and 11 will be followed by the respective sliders 29 and 33. The two potentiometers 27 and 34 are connected in series with an A. C. or D. C. voltage source over conductors 35 and 36 and a resistor 37. Also connected in parallel with the resistor elements 28 and 32 is a recording amplifier 39 which is supplied with bias current from an erase and bias oscillator 40.

The output of the recording amplifier 39 is fed to a swinger 41 of a switch 42, while a second output from the oscillator 40 is fed to a swinger 43 of the switch 42. A third swinger 45 is mechanically connected to the swingers 41 and 43 as indicated by the dotted lines 44, all three swingers being operable by either a relay 46 or manually. With the swinger 41 in its upper position, the output of the recording amplifier 39 is fed to a magnetic record-reproduce head 47, while the output of the oscillator 40 is fed over conductor 48 to a magnetic erase head 49. The heads 47 and 49 are associated with the magnetic control track film 50.

During a first rehearsal, the motor driven attenuator 8 is adjusted and mechanically or otherwise held so that the slider 29 is and remains at its central or other fixed position on the resistor 28. Thus, the amplitude of the output of the reproduce head 6 is varied by the manual operation of the knob 31 controlling the attenuator 11 and the potentiometer 34. As the slider 33 is moved over its resistor element 32, voltage variations of the A. C. or D. C. source will be recorded by record-reproduce head 47 on control track film 50, this voltage varying according to the manual adjustments of attenuator 11. Simultaneously, erase current is applied to erase head 49 to insure a clean recording area. During this rehearsal, switch 52 is open so that no recording is made of the rehearsal run while switch 53 is closed.

To automatically repeat the adjustments made by attenuator 11, the slider 33 of potentiometer 34 is set at its central or other fixed position to provide the same attenuation introduced previously by attenuator 8 when attenuator 8 was held fixed. During this operation, the switch 42 is thrown to its second or lower position. In the second position of switch 42, swinger 41 connects the output of the recording amplifier 39 over conductor 54 to a record-reproduce head 55. Simultaneously, the swinger 43 connects the output of the oscillator 40 over conductor 56 to erase head 57, erase head 57 and record-

reproduce head 55 being associated with the second control track film 58. Swinger 45 in its second position connects the output of record-reproduce head 47 over conductors 60 and 61 to a control signal amplifier 62, the output of which is fed to motor 26 over conductor 63. The motor 26 thus will vary the audio attenuator 8 in the same manner as the attenuator 11 was varied during the first rehearsal, since the attenuators 8 and 11 are identical and the potentiometers 27 and 34 are identical.

During this automatic rerecording operation, a new control track is recorded by record-reproduce head 55 on control track film 58. Also during this rerecording operation, manual changes may be made in the amplitude of the audio signal by manipulation of the knob 31 of attenuator 11. Thus, the new control track may be a combination of the original manipulation of attenuator 11 plus any changes made by the subsequent manual manipulation of attenuator 11. Thus, the control track 58 will contain the new variations in amplitude of the signal.

If this second or last rehearsal was satisfactory, the switch 52 may be closed and the control track on film 58 reproduced to control the amplitude level of the signal being recorded by recorder 15. During this operation, the switch 42 is in its first or upper position shown in the drawing whereby record-reproduce head 55 is connected over conductor 54 and swinger 45 to the signal control amplifier 62 and thus to motor 26. Since there is no control track on film 58 during the first rehearsal, the motor 26 will not be energized. During any subsequent automatically controlled recording operation, additional variations may be made by manually adjusting the attenuator 11, a new control track being recorded on either film 50 or film 58. If no control track is to be recorded, switch 53 may be opened.

The above system, therefore, requires a minimum of equipment for obtaining an automatic rerecording operation and has the advantage of utilizing standard audio attenuators now found on mixing consoles. The additional equipment required includes the potentiometers 27 and 34 and the motor 26. Thus, such a system provides not only automatic control but manual control during the automatic control which does not interfere in any manner with the automatic operation of the system.

I claim:

1. In a sound rerecording system, the combination of a source of signals, a transmission circuit for signals from said source, said transmission circuit including a pair of signal amplitude attenuators connected together, a pair of voltage varying devices, each device being mechanically connected to a separate one of said attenuators, a source of control current, said voltage varying devices being connected together and to said source of control current, said voltage varying devices being adjustable in accordance with the adjustments of said attenuators, means for recording variations in said control current produced by adjustments of said voltage varying devices, and means for recording said signals as varied by said attenuators.

2. A sound rerecording system in accordance with claim 1 in which said attenuators are connected in series and said voltage varying devices are connected in series.

3. A sound rerecording system in accordance with claim 1 in which said first-mentioned means includes a

recording system connected to said source of control current and said voltage varying devices.

4. A sound rerecording system in accordance with claim 1 in which a motor is provided for varying one of said attenuators and one of said voltage varying devices and manually operable means are provided for varying the other of said attenuators and voltage varying devices.

5. A sound rerecording system in accordance with claim 4 in which said motor is connected to said first-mentioned means for actuating the attenuator connected thereto, the recorded control current energizing said motor.

6. An automatic rerecording system comprising a source of audio signals, a source of control track signals, a recorder of said audio signals, a recorder of said control signals, means for connecting said source of audio signals to said recorder thereof, said means including a pair of attenuators for varying the level of said audio signals, means for connecting said source of control track signals to the recorder thereof, said means including a pair of potentiometers for varying the level of said control track signals, each one of said potentiometers being mechanically connected to a separate one of said attenuators, adjustment of one of said attenuators simultaneously adjusting its connected potentiometers, and individual means for adjusting each of said attenuators.

7. An automatic rerecording system in accordance with claim 6 in which one of said individual means is an manually operated element and said other individual means is a motor energized from a recorded control track signal.

8. An automatic rerecording system in accordance with claim 7 in which said recorder for said control signals includes a control track film on which said control track signals are recorded, means for connecting said recorder to said motor, a second control track film, and means for recording said control track signals on said second film during the connection of said recorder to said motor.

9. An automatic rerecording system in accordance with claim 8 in which said recorder of said audio signals is adapted to simultaneously record a plurality of audio signals.

10. In a sound rerecording system for a source of signals, the combination of a transmission circuit for signals from said source, said transmission circuit including signal amplitude attenuating means, a pair of voltage varying devices, one of which is mechanically connected to said signal amplitude attenuating means, a source of control current, at least one of said voltage varying devices being connected to said source of control current, one of said voltage varying devices being adjustable in accordance with the adjustment of said signal amplitude attenuating means, means for recording variations in said control current produced by adjustments of said one voltage varying device connected to said signal amplitude attenuating means, and motor means for actuating said signal amplitude attenuating means and said one voltage varying device.

11. A sound recording system in accordance with claim 10 in which manually actuated means is provided for actuating said other voltage varying device.
